HANDRAIL COUPLING

William J. Horgan, Jr., Pittsburgh, Pa., assignor to
Blumcraft of Pittsburgh, Pittsburgh, Pa.

Filed Feb. 10, 1972, Ser. No. 225,376

Term of patent 14 years

Int. Cl. D8—08

U.S. Cl. D8—236

Fig. 1

*Fig. 2**Fig. 3**Fig. 4**Fig. 5*

FIG. 1 is a perspective view taken from the left front side of a handrail coupling embodying my new design, shown in its environmental relationship to a handrail and post;

FIG. 2 is a perspective view taken on a greatly enlarged scale from the right rear side of a single handrail coupling shown in FIG. 1;

FIG. 3 is a top view on a reduced scale of the embodiment shown in FIG. 2;

FIG. 4 is a front elevation on a reduced scale of the embodiment shown in FIG. 2; and

FIG. 5 is a left side elevation on a reduced scale of the embodiment shown in FIG. 2.

The rear elevation is identical to the front elevation.

The handrail, posts and supporting slab shown in phantom lines in FIG. 1 form no part of the design, but have been included for environmental purposes only.

I claim:

The ornamental design for a handrail coupling, as shown and described.
